UNITED STATES PATENT OFFICE.

WILLIAM F. J. CASEY, OF KINGSTON, ONTARIO, CANADA, ASSIGNOR TO LOCOMOTIVE SUPERHEATER COMPANY, OF NEW YORK, N. Y., A CORPORATION OF DELAWARE.

STEAM-SUPERHEATER.

1,140,116.

Specification of Letters Patent.

Patented May 18, 1915.

Application filed October 27, 1913. Serial No. 797,598.

To all whom it may concern:

Be it known that I, WILLIAM F. J. CASEY, of the city of Kingston, in the Province of Ontario and Dominion of Canada, have invented certain new and useful Improvements in Steam-Superheaters, of which the following is a full, clear, and exact description.

This invention relates to improvements in superheaters, preferably for use in connection with locomotive boilers, and the object is to provide a superheater of simple, inexpensive and durable construction composed of a minimum number of parts.

15 A further object is to provide a superheater in which the course of the steam is made as direct as possible.

Further objects and advantages will be apparent to those skilled in the art to which 20 this invention relates from the following description.

At the present time, superheaters consist as a rule of a number of superheating units or loops connected at their opposite ends 25 to headers. Each loop as a rule occupies a single fire tube of the boiler, these tubes being preferably spaced equidistantly. As there are obviously as many superheating units as fire tubes, it will be seen that a large 30 number of connections require to be made between these units and the headers.

In the present invention, the fire tubes of the boiler are arranged in vertical rows as usual, but the spacing of these vertical tube 35 rows is irregular, so that the tubes are arranged in spaced groups. The superheater units are arranged in the form of a number of loops arranged in a horizontal plane, each loop entering a fire tube, so that each unit 40 passes through a plurality of fire tubes. The heating units are preferably arranged in pairs one below the other. The wet or saturated steam is delivered from the boiler into a header having a plurality of branches 45 arranged in front of alternate spaces between the groups of fire tubes. These header branches are connected to one end of each heating unit, the opposite ends of said units being connected to collectors disposed intermediate the header branches. These collectors are arranged in line with and are merely extensions of the steam pipes to the engine cylinders, so that the steam travels 50 in the most direct path possible.

In the drawings which illustrate the invention:—Figure 1 is a half front elevation of the superheater partly in section. Fig. 2 is a vertical sectional view on the line 2—2, Fig. 1. Fig. 3 is a fragmentary sectional view on the line 3—3, Fig. 1. Fig. 4 is a sectional view of the connecting means between the heating units and header or collector.

Referring more particularly to the drawings, 5 designates a boiler shell having front and back tube plates 6 and 7 respectively, 55 between which are supported a plurality of fire tubes 8. The smoke box at the front end of the boiler in which part of the superheater is located is designated 9. The fire tubes are preferably arranged in vertical 60 rows, as shown in Fig. 1, said rows being spaced alternately close together and far apart, as shown in Figs. 1 and 3, so that the fire tubes are divided into a plurality of groups.

75 The wet or saturated steam header 10 and the dry or superheated steam collectors 11 are formed in a single casting, having at the top a neck 12 to which the steam supply pipe is connected and at the bottom a pair 80 of necks 13 located one on each side of the center, so as to be connected directly to the engine cylinders by a short length of pipe. The wet steam header is provided with three 85 depending branches, namely, a center branch 14 and two comparatively small side branches 15. The center branch 14 is located opposite the space between the two central groups of fire tubes, and the small 90 branches 15 are located just beyond the outer groups of fire tubes. The dry steam collectors 11 are located intermediate the branches 14 and 15 and opposite the spaces 95 between fire tube groups. Each of these collectors is approximately the same size as the large header branch 14, that is to say, the two collectors have approximately the same capacity as the three header branches.

The header branches and collectors are 100 suitably tapered to give a uniform distribution at all points, as is shown in Fig. 2. The lower ends of each of the header branches are connected by integral straps or stays 16 with the lower ends of the collectors, while the upper ends of the collectors are connected by similar but shorter stays 17 with the header 10, these stays 105 being spaced so as to leave a clear air space

18 between the end of the dry steam collector and the wet steam header. This air space prevents transference of heat from the superheated to the unsuperheated steam at the only point where the several passages meet. The stays 16 and 17 rigidly connect the wet and dry steam passages, so that there cannot be any relative movement between them, which movement would obviously produce an unnecessary stressing of the superheating units connected between them and would also cause leaking at the joints.

The superheating element consists of a plurality of units 19 each formed preferably of four straight tubes 20 connected in series by return bends 21 or loops 22. In the arrangement shown in the drawing, each unit 19 consists of a tube extending rearwardly from a wet steam header branch and through to the rear of a fire tube where it is connected by a return bend with a forwardly extending tube, which is looped or bent on itself at 22 and extends to the rear of the next fire tube. Another return bend is used to connect this looped tube with the forwardly extending tube, which in turn connects with a collector 11. The unit thus formed is disposed in a horizontal plane, so that it passes into each fire tube across the group. The arrangement of fire tubes in alternately adjacent and separated vertical rows, as previously stated, causes there to be two vertical rows of fire tubes between each collector and the header branches on either side thereof. In this way, each heating unit passes through two fire tubes. By multiplying the number of fire tubes, the groups may be made to contain three vertical rows, so that each heating unit passes through three fire tubes. On the other hand, with the present number of tubes, the outer branches 15 may be eliminated by enlarging the central branch 14, and each collector placed outside the tube groups, so that the heating units pass through four tubes.

The connection between the ends of the heating units and the header branches or collectors may be of any suitable type, but is preferably of the star type shown in the drawings, as by this means four units may be connected to a single opening in the branch or collector, thus strengthening the latter. This star connection consists of a body 23, having a tapered neck 24 screw threaded into the branch or collector. A suitable number of externally threaded nipples 25 radiate from the body. The ends of the units are taper screw threaded into the elbows 26 provided with flanges 27 engaged by suitable coupling nuts 28, which screw on to the nipples 25. The seat surface 29 on the flange end of each elbow is preferably spherically curved, and cooper-

ates with a similarly curved seat on the nipple, so that a tight joint may be readily maintained.

The wet steam enters the superheater through the neck 12 and flows into the branches 14 and 15 in properly proportioned amounts. The tapering branches distribute the steam evenly to all the heating units. The steam then flows through the units passing back and forth through the fire tubes, and is finally delivered into the collectors 11 from which it passes directly to the pipes connecting with the cylinders, without the necessity of flowing through the tortuous passages of any header arrangement. It will be seen from the drawings that the steam travels the length of the fire tubes four times in passing through each heating unit, and thereby becomes thoroughly dried and superheated so as to have the increased efficiency desired.

From the foregoing description, it will be readily seen that the superheater consists of a very small number of parts of great simplicity and durability. The front casting is much lighter than the usual type, much simpler to make and much stronger, owing to the reduced number of openings. The superheating may be said to be in two stages, that is, each heating unit is surrounded by two entirely separate and distinct currents of hot gases, so that should the heat in one fire tube be below normal, the heat in another tube will prevent the mingling of imperfectly superheated with perfectly superheated steam. The tubes themselves are perfectly straight and not upset, so that they may be supplied at a minimum cost. Any heating unit may be removed independently of all others for cleaning or repair.

Having thus described my invention, what I claim is:—

1. In a superheater, the combination with fire tubes arranged in horizontally separated groups each group having a plurality of horizontally disposed tubes, of a wet steam distributing header having branches depending integrally from said header in line with alternate spaces between tube groups, an engine steam pipe for each side of the engine having a single vertical prolongation in line with one of the remaining spaces between tube groups, and superheating units connected between a branch and one of the said prolongations, each unit traversing all the horizontally disposed tubes of the group.

2. In a superheater, the combination with fire tubes arranged in horizontally separated groups each group having a plurality of horizontally disposed tubes, of a wet steam distributing header having branches depending integrally from said header in line with alternate spaces between tube groups,

- groups, an engine steam pipe for each side of the engine having a single vertical prolongation in line with one of the remaining spaces between tube groups, and superheating units connected between a branch and one of the said prolongations, each unit traversing all the horizontally disposed tubes of the group, the header, branches, and prolongations being integrally united together.
- 10 3. In a superheater, the combination with four horizontally disposed and spaced groups of flue tubes each group having two vertical rows and the distance between groups being greater than the distance between rows, of a wet steam distributing header having a branch depending integrally from said header on each side of all the groups and a third branch depending integrally between the second and third
- 15 groups, an engine steam pipe for each side of the engine having a single vertical prolongation in line with the spaces between the first and second and between the third and fourth groups respectively, and superheating units connected between the branches and the prolongations, each unit traversing each horizontal flue tube of the group.
- 20 4. In a superheater, the combination with fire tubes arranged in horizontally separated
- 25 groups each group comprising a plurality of vertical rows of horizontally disposed tubes,
- of a wet steam distributing header having branches depending integrally from said header in line with alternate spaces between tube groups, an independent steam conduit 35 for each side of the engine leading to the steam chest and having a portion in line with one of the remaining spaces between tube groups, and superheater units connected between branches and engine pipes, 40 each unit traversing all the horizontally disposed tubes of the group.
5. In a superheater, the combination with fire tubes arranged in horizontally separated groups, each group comprising a plurality 45 of vertical rows of horizontally disposed tubes, of a wet steam distributing header having branches depending integrally from said header in line with alternate spaces between tube groups, an independent steam conduit 50 for each side of the engine leading to the steam chest and having a portion in line with one of the remaining spaces between tube groups, and superheater units connected between branches and engine 55 pipes.

In witness whereof, I have hereunto set my hand, in the presence of two witnesses.

WILLIAM F. J. CASEY.
